INSERT FOR INDUSTRIAL SHIPPING CONTAINER

Ralph V. Bardell, Homewood, Ill., assignor to Growth International Industries Corp., a corporation of Delaware

Filed Jan. 9, 1969, Ser. No. 15,266

Term of patent 14 years

Int. Cl. D9—99

U.S. Cl. D9—253

FIG. 1 is a insert for industrial shipping container showing my new design;

FIG. 2 is a top plan view thereof;

FIG. 3 is a front view thereof, the front and side views being substantially mirror images thereof; and

FIG. 4 is a bottom plan view thereof.

I claim:

The ornamental design for a insert for industrial shipping container, as shown.
